UNITED STATES PATENT OFFICE.

CHESTER E. WARNER, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

CIRCUIT-CONTROLLING DEVICE.

Application filed September 7, 1920, Serial No. 408,578. Renewed November 27, 1925.

My invention relates to circuit controlling devices, and particularly to pull switch sockets or receptacles and switch mechanism for such sockets.

5 One of the objects of my invention is to provide a pull switch socket which will be efficient and durable in use, simple in construction and cheap to manufacture.

10 A further object is to provide a pull socket having a switch mechanism which is capable of handling currents of larger wattage than heretofore. Such sockets are now called upon to carry current for electric flat irons, suction cleaners and other devices taking 15 more current than the sockets commonly in use are capable of handling safely, and in view of the limited space available in the ordinary socket it has been a matter of great difficulty to produce a pull switch mechanism which could be safely employed in a socket at the present time. This is accomplished in the socket and switch mechanism forming the subject of the present invention.

20 Further objects will appear from the detailed description to follow and from the appended claims.

In the drawings, in which an embodiment of my invention is shown,

25 Fig. 1 is a plan view of a pull switch socket of the angle type with the cap removed;

Fig. 2 is an axial section on the line 2—2 of Fig. 1;

30 Fig. 3 is a section on the line 3—3 of Fig. 2;

Fig. 4 is a section on the line 4—4 of Fig. 1;

Fig. 5 is a section on the line 5—5 of Fig. 4;

40 Fig. 6 is a section on the line 6—6 of Fig. 4;

Fig. 7 is a detail view of the switch mechanism, the switch being shown in the "on" position;

45 Fig. 8 is a section on the line 8—8 of Fig. 1;

Fig. 9 is a detail view similar to Fig. 7, but showing the switch in the "off" position;

50 Fig. 10 is a top plan view of a combined switch arm and switch spindle employed in the switch mechanism, and

Fig. 11 shows in perspective a spring-shifting member and a rotary ratchet member with a cam carried thereby for moving said spring-shifting member.

The construction shown in the drawings comprises in a general way, a pull switch angle socket having an insulating base 10, shell and center contacts 11 and 12 respectively, supported by the insulating base 10, wiring terminals 13 and 14 for the contacts 11 and 12 respectively, switch mechanism 15 for controlling the circuit between the center contact and its wiring terminal 14 and an ornamental sheet metal casing 16 for housing the insulating base 10 and the various parts supported thereby.

60 The threaded shell contact 11 is always electrically connected with its wiring terminal 13, by means of a screw 17, the head 70 of which engages the flange 18 of the threaded shell contact (Fig. 3) and the upper end of which screw is threaded into the binding plate 19 of the wiring terminal 13 (Fig. 1). An insulating fibre lining 20 surrounds 75 the threaded contact and insulates it from the sheet metal ornamental casing 16. The cap 21 of the sheet metal casing is readily removable to permit access to the wiring terminals and switch mechanism.

80 The switch mechanism 15 controls the circuit between two spring contact fingers 22 and 23 (Fig. 8) the spring contact finger 22 being always electrically connected with the wiring terminal 14 and the spring contact 85 finger 23 being always electrically connected with the center contact 12. As shown in Fig. 8 the base portion of spring contact finger 22 is clamped underneath the base portion of the binding plate member 24, by 90 means of the screw 25. The base portion of the spring contact finger 23 is held underneath the head of the eyelet 26, the head at the other end of this eyelet engaging and holding the base portion of the center contact 12, whereby the eyelet 26 not only serves to electrically connect the center contact 12 with the spring contact finger 24 but also 95 serves to mechanically hold these parts in place on the insulating base 10.

100 The switch mechanism which controls the circuit between the spring contact fingers 22 and 23 comprises a pivoted switch arm 27, oscillatable back and forth from a position in which it engages the contacts 22 and 23 105 to a position in which it is out of engagement therewith, a coil tension spring 28, one end of which bears on the oscillatable switch arm 27, a pivoted spring-shifting member 29 on which the other end of the 110

spring 28 bears, suitable shifting mechanism for causing the member 29 to oscillate back and forth, and a pull chain 30 for manual operation of the shifting mechanism.

5 The shifting mechanism comprises an oscillatable driving ratchet member 31, including a chain rail to which the pull chain 30 is secured, and a rotatable driven ratchet member 32 to which is secured a cam or eccentric 33, which operates in a slot 34 in the oscillatable spring-shifting member 29. (Figs. 4, 6, 7, 9 and 11). The oscillatable spring-shifting member 29 is pivotally mounted on a T-shaped bearing member 35 (Figs. 1 and 7) formed as an integral part of the switch frame 36, the end of the oscillatable spring-shifting member 29 being bifurcated as indicated at 37, and straddling the shank of the T-shaped bearing and serving to prevent the oscillatable member 29 from slipping off the bearing.

The switch arm 27 is shown as comprising a piece of bent wire having a looped portion 38 to which the end of the spring 28 may be attached, and having a shaft or spindle portion 39 which extends through suitable bearing openings in the standards 40 and 41 of the switch frame 36. This combined switch arm and spindle is shown by itself 30 in Fig. 10. The spindle portion 39 serves as a bearing for the oscillatable ratchet member or chain rail 31 and also for the driven ratchet member 32.

The oscillatable spring-shifting member 29 is provided with an eye portion 42 to which one end of the spring 28 is secured, and is also provided with a kick-off projection 43 for engagement with the switch arm 27 in case the yielding force exerted by the spring 28 does not start the switch arm to moving quickly enough. A stop lug 44 may be struck up from the switch frame 36 to limit the upward oscillation of the switch arm 27. For insulating the contact brush member 45 from the switch arm 27 the bent end 46 of the switch arm is embedded in an insulating block 47 to which the brush 45 is secured.

For returning the pull chain 30 after it 50 has been pulled down, and for holding the driving ratchet member 31 against the driven ratchet member 32, a coil torsion and compression spring 48 is provided which surrounds the journal member 39 and has 55 one end secured to the frame upright 41 and the other end secured to either one of the two lugs 49 struck up from the driving ratchet member 31.

To limit the return movement of the pull 60 chain 30 under the influence of the torsion spring 48 a stop member 50 may be struck up from the switch frame 36, this stop projection 50 being located in position to be engaged by the hook 51 to which the pull 65 chain 30 is secured.

The cam 33 is shown as a circular sheet metal disc secured to the driven ratchet member 32 by means of a rivet 52 (Figs. 4 and 11). The shaft portion 49 of the switch arm extends through a hole adjacent 70 the edge of this cam 33, thus serving to keep the cam disc 33 from twisting around on the rivet 52.

The operation of the switch is as follows:

Assuming that the switch is in the position shown in Figs. 2, 5 and 7, which is the "on" position, and it is desired to turn the switch to "off" position, the pull chain 30 is pulled down and released. The pulling down of the pull chain moves the oscillatable driving ratchet member or chain rail 31 through a movement of 180 degrees, and this movement of the driving ratchet member also moves the driven ratchet member through the engagement of the ratchet teeth 53 of the driving ratchet member with the edges of the openings 54 in the driven ratchet member. This movement of this driven ratchet member through 180 degrees moves the cam 33 from its extreme lower position shown in Fig. 7 to the extreme upper position shown in Fig. 9. This movement of the cam 33 oscillates the spring-shifting member 29 from its extreme lower position shown in Fig. 7 to its extreme upper position shown in Fig. 9. Immediately after the spring 28 is shifted past the dead center line between the spring connection at 38 and the axis of the spindle 39, the spring exerts a force tending to move the switch 100 arm 27 upwardly to move the brush 45 out of engagement with the contacts 22 and 23. This breaks the circuit at two points between the center contact 12 and its wiring terminal 14. As stated above, if the switch arm 27 should be inclined to stick, the kick-off projection 43 will engage the switch arm to give it a start, after which it will move quickly under the influence of the spring 28. The switch arm is brought 110 to a stop against the stop projection 44 on the switch frame.

By a similar operation, the switch will be thrown to "on" position by the succeeding downward pull on the pull chain 30.

What I claim as new and desire to secure by Letters Patent of the United States is:—

1. A pull switch receptacle comprising receptacle contacts and switch mechanism comprising a piece of wire bent to form a shaft portion, a switch arm portion and a spring attaching portion, a shifting spring attached to said spring attaching portion, a spring shifting member and ratchet mechanism rotatably mounted on said shaft portion for operating said spring shifting member.

2. A switch mechanism, comprising a piece of wire bent to form a switch arm por-

tion and a spring attaching portion, an insulating member in which said portions are embedded, a contact member straddling said insulating member, and a shiftable spring secured to said spring attaching portion.

3. A switch mechanism comprising a switch frame, a spindle journaled in said frame, a switch arm on one end of said spindle beyond said frame, a rotating member including a cam supported on said spindle, an oscillating ratchet member for turning said rotating member continuously in one direction, a spring shifting member and a spring acting between said spring shifting member and said switch arm, said spring

shifting member being moved by said cam.

4. A switch mechanism comprising a switch frame, a spindle supported to oscillate in said frame, a rotary member turning on said spindle, a ratchet member oscillating on said spindle and driving said rotary member, a switch contact member oscillating with said spindle, and means intermediate said rotary member and said switch contact member for rocking said spindle and said switch contact member with a snap action in both directions.

In witness whereof, I have hereunto subscribed my name.

CHESTER E. WARNER.
